STEEL TAPE BRAKE

Emmitt L. Stewart, Oklahoma City, Okla.

Application May 24, 1934, Serial No. 727,371

4 Claims. (Cl. 242—84.8)

This invention relates to the class of measuring tapes and while it is applicable to all types of tapes, is designed primarily for use in connection with steel tapes of the character designed for measuring the depth of liquids in storage tanks for the purpose of determining the quantity of the same.

The primary object of the present invention is to provide a novel means for controlling the paying out of steel tape from the reel, the tapes in association with which the present device is designed for use, usually being unwound by means of a weight attached to the free end thereof.

Another object of the invention is to provide a braking device for use upon wound steel tapes, which is readily controlled by the thumb of the hand in which the tape is being held while it is being unwound for use.

At present, wound steel tapes are provided which are mounted upon carrying handles, which are unwound for introduction into storage tanks or similar receptacles for determining the quantity of liquid in the tank, the free end of the tape having a weight or plumb attached thereto to cause the tape to unwind freely. The present practice is to control the unwinding of the tape by the application of the thumb to the reel and because of the fact that the tape is of thin steel, this practice frequently results in severe cuts to the user of the tape. The present invention is designed to overcome this difficulty by the mounting of a braking device upon the carrying frame of the tape, which is constantly resiliently applied to the tape and which has an extension upon which the thumb or finger of the hand holding the frame may be placed so as to shift the portion which normally contacts the tape, to allow the tape to unroll freely.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view partly in side elevation and partly in section of a steel tape holder showing the application of the present invention thereto.

Figure 2 is a sectional view taken on the line 2—2 of Figure 1.

Referring to the drawing wherein like numerals of reference designate corresponding parts throughout the views, the numeral 1 indicates a frame of the type in which is mounted the steel gauge line or tape which is here indicated by the numeral 2. These tapes are marketed by steel tool manufacturers and while there are a variety of forms, the present illustration shows one form or variety which is commonly used. This tape is wound up in the frame 1 upon a shaft 3 by means of a foldable handle 4 and the frame at one side has attached thereto the carrying handle 5 by which the device is held while the tape is being unwound or wound up.

The numeral 6 indicates an arcuate steel arm which is secured at one end between the end of the handle 5 and the frame 1 and which curves partway around the tape, terminating in the angular extension 7 which is disposed in a line substantially at right angles to the line of the handle 5 and substantially radially of the reel. This angular extension carries a centrally slotted wiper element 8 through which the tape 2 passes and by which the liquid is wiped from the tape as the latter is wound up. This wiper and supporting means therefor constitutes the subject-matter for my copending application, Ser. No. 714,707, filed March 8, 1934.

In carrying out the present invention, the arm 6, which in the copending application referred to, serves the solitary purpose of supporting the wiper 8, is also employed as a supporting means for the brake element. The inner or concave surface of the arm is provided with the spaced ears 9 which may be formed integral with the side edges of the arm and turned inwardly to spaced parallel relation in the manner illustrated. Disposed to extend through the frame 1 between the arm 6 and the reel 2, is the flat oscillatable arm 10 which positions between the ears 9 and which has extending from its opposite edges the trunnions or pivot pins 11 which are mounted in the ears in the manner illustrated. The upper end of this arm is bent to form the thumb portion 12 which is disposed substantially parallel with and overlies the handle 5. At its opposite end beyond the trunnions 11, the oscillatable arm 10 has attached thereto, one end of the pin 13, which passes through the fixed arm 6 and is threaded at its opposite end to receive the wing nut 14. Between this wing nut and the fixed

arm 6 is an expansion coil spring 15 which, by its tendency to expand and because of its engagement at one end with the fixed arm 6, and at its other end with the wing nut 14, tends to draw the lower end of the oscillatable arm 10 in toward the fixed arm.

Attached to the forward face of the oscillatable arm 10 above the trunnions 11 is a fiber brake shoe 16, which is so arranged that when the oscillatable arm is shifted by the spring 15, it will be brought into contact with the steel tape 2.

From the foregoing, it will be readily apparent that any tendency of the tape to unwind is constantly opposed by the brake mechanism which is under the control of the spring 15. When the tape is to be unwound or paid out, the operator depresses the laterally extending portion 12 of the oscillatable arm, thereby reTRACTING the shoe 16 and thus freeing the tape for unwinding.

What is claimed is:—

1. In a steel tape having a frame and handle connected therewith, an arm secured to the frame, a second arm oscillatably mounted upon the first arm, friction means carried by the second arm for contact with the tape, means for oscillating the arm to remove the friction means from the tape, and resilient means normally urging the second arm to oscillate in a direction to bring the friction means against the tape.
2. In a steel tape, a frame, a handle attached to the frame, an arm fixed to a portion of the device, a second arm disposed between the fixed

arm and the tape and oscillatably mounted upon the fixed arm, said second arm having a laterally directed portion overlying said handle, a friction body carried by the second arm for contact with the tape, and resilient means in engagement with and normally urging the second arm to oscillate in a direction to bring the friction means into contact with the tape.

3. In a measuring tape structure including a frame, a handle, and a measuring tape wound up in the frame, an arm secured rigidly to the device, a pair of spaced ears carried by said arm, a second arm disposed between the tape and the first arm and oscillatably mounted between said ears, said second arm having a laterally extending terminal portion overlying said handle, a pin secured at one end to the oscillatable arm and passing through the fixed arm and having a body attached to its other end, a spring surrounding said pin between said body and the fixed arm and normally tending to oscillate the second arm, and a friction body carried by the second arm in position for contact with the tape.

4. In a device of the character described, a rectangular frame, a steel tape wound within the frame, a handle carried by the frame, an arm extending through the frame and mounted for oscillation therein relative to the tape, means forming the continuation at one end of the arm and overlying the handle for facilitating the oscillation of the arm, and resilient means normally urging said arm toward the tape.
